[57] CLAIM

The ornamental design for a bracelet or similar article, substantially as shown and described.

DESCRIPTION

FIG. 1 is a top plan view of a bracelet or similar article showing my new design portions of the continuous neckchain being broken away for convenience of illustration;

FIG. 2 is a bottom plan view thereof;

FIG. 3 is a side elevational view thereof;

FIG. 4 is a top plan view corresponding to the left hand portion of FIG. 1, showing the clasp thereof in opened condition; and

FIG. 5 is an end elevational view thereof.

FIG. 1.

FIG. 2.

FIG. 3.

FIG. 4.

FIG. 5.
